ACCORDION

Walter Gollnick, Chicago, Ill.

Application May 16, 1938, Serial No. 208,196

4 Claims. (Cl. 84—376)

This invention relates to improvements in accordions.

The principal object of the invention is to provide means whereby, during the playing of an accordion, vibrato effects can be produced.

Another object of the invention is to provide a mechanism which may be installed in a conventional accordion for producing vibrato effects.

Other objects relate to various features and arrangement of parts which will be apparent from a consideration of the following specification and accompanying drawings, wherein:

Fig. 1 is a broken top plan view of a conventional accordion showing an embodiment of the improvements installed therein;

Fig. 2 is a sectional view taken on line 2—2 of Fig. 1;

Fig. 3 is a side elevation of an accordion broken away for illustrating the vibrato producing mechanism installed in the bellows compartment of the accordion; and

Fig. 4 is a broken sectional view of a conventional accordion showing a modification of the improvements.

In the drawings, 10 indicates generally a conventional accordion provided with end casings 11 and 12 which support the keys, reeds, and other conventional portions of the instrument. Connecting the members 11 and 12 is a conventional bellows 13. The means shown in Figs. 1, 2 and 3 for producing the vibrato effect is adapted to be installed in the bellows compartment 14 as, for example, by attaching the same to the reed blocks or other relatively firm portions of the instrument. The position of attachment of the vibrato-producing means is not particularly important so long as it does not interfere with the usual operation of the instrument and is located in or in communication with the bellows compartment 14.

The mechanism shown in Figs. 1 to 3, inclusive, comprises an expandible-contractible member indicated generally by the numeral 16. The member 16 is in the form of a bellows and comprises a base 17 which, by means of a clip or mounting plate 18, may be attached to the reed blocks by screws 19 as shown in Fig. 3. Hinged to the base or relatively stationary member 17 is a movable bellows member 20 and connected thereto also by the flexible bellows member 21. The member 20 is arranged to be moved toward and away from the member 17 by a motor such as an electric motor 22 which may likewise be mounted in the bellows compartment 14 upon the blocks 15.

The motor may be provided, as shown in Fig. 3, with a reduction gear housing 23 within which, on the motor shaft 24, is mounted a driving pinion 25 which drives a gear 26 journaled in the housing 23 and which rotates a stub shaft 27 provided with a crank arm 28 at its outer end. The arm 28 carries a pin or connecting member 29 which passes through a recess in a link 30 swingably attached to the projecting end of a short bar 31 which is secured to the bellows member 10. The rotation of the motor 22 will, by this mechanism, operate the bellows member 20 in a direction toward and away from the relatively stationary member 17. The effect of this movement is to vary the effective air space of the compartment 14 and thus produce successive pressure pulsations and rarefactions of the air pressure obtaining in the bellows during the playing thereof, thereby producing the vibrato effect.

For the purpose of avoiding the formation of partial vacuum within the bellows 16 and successive compressions of air within the same, the bellows is shown in Figs. 1, 2 and 3 as communicating with the atmosphere through a flexible conduit 32. Thus, during the operation of the bellows 16, a reciprocating movement of air is produced within the conduit 32 and alternative compressions and rarefactions of the air within the bellows itself is avoided. The load on the motor is thus reduced.

Means may be provided for varying the throw of the crank pin 29 such as by the provision of additional apertures 33 and 34 in the arm 28 in either of which the crank pin 29 may be inserted, when desired, for increasing or decreasing the distance of travel of the bellows member 20. By placing the crank pin in the aperture 34, for example, the bellows member 20 will swing through a greater arc than when the pin 29 is in the receiving recess more closely located with reference to the axis of rotation.

Where the motor is electrically actuated, it is desirable to provide a switch 35 whereby the player can start or stop the motor conveniently, the switch being connected electrically to a receptacle 36 in which a small conduit plug 37 of the conductor 38 may be inserted for convenient attachment to any convenient source of electric energy.

When the mechanism described is in use, the accordion will, of course, operate in its usual manner but the player may, by operation of the switch 35, start the motor, thereby producing the desired vibrato effect during such period of

50

55

time or portion of the selection being played as he desires.

In Fig. 4 of the drawings, the same vibrato-producing mechanism is shown located on the exterior of the casing or head of the instrument and the various parts are indicated by corresponding references which have been primed. The device is shown enclosed in a housing 39. The conduit 32' communicates with the bellows compartment 14' whereby the latter communicates with the interior of the bellows 16'. When the bellows member 20' moves toward the member 17, air is forced through the tube 32' into the chamber 14', thereby producing a slight increase of pressure in the chamber 14'. When the member 20' moves away from member 17', air is drawn from chamber 14' into the bellows 16' thus producing a slight rarefaction in the prevailing pressure in the chamber 14'. The vibrato effect is thus produced by the pumping action of the bellows 16' producing alternate pressure pulsations and rarefactions as will be clear.

While I have shown and described certain embodiments of my improvements for the purpose of illustration, it will be seen that various changes in the location and construction of parts may be resorted to without departing from the spirit of the invention as defined by the appended claims.

I claim:

1. An accordion comprising a bellows compartment, and means for producing a vibrato effect during use of the accordion comprising a bellows

acting within the bellows compartment for displacing air therein for creating alternate recurring pressure pulsations and rarefactions of the air in said compartment, and means comprising a motor for operating said bellows.

5

2. An accordion comprising a bellows compartment, means for producing a vibrato effect comprising an air displaceable bellows communicating with said compartment for effecting rapidly recurring variations in air pressure in said compartment, and means independent of the flow of air in said bellows compartment for operating said second bellows.

10

3. In an accordion having a bellows compartment, means for producing a vibrato effect comprising a member in said compartment operable for successively increasing and decreasing rapidly the available air space of said compartment, and means independent of the flow of air in said bellows compartment for operating said member.

15

4. In an accordion having a bellows compartment, means for producing a vibrato effect comprising a hollow air displacing member in said compartment comprising a bellows operable in opposite directions alternately for producing rapidly succeeding pulsations and rarefactions of air pressure in said compartment, means for operating said member, and means independent of the air in said bellows compartment for varying the value of said pulsations and rarefactions for varying the vibrato effect.
